UNITED STATES PATENT OFFICE

HENRY R. McCLEARY, OF CHICAGO, ILLINOIS, ASSIGNOR TO WILSON-JONES COMPANY,
OF CHICAGO, ILLINOIS, A CORPORATION OF MASSACHUSETTS

PAMPHLET BINDER

Application filed August 12, 1929. Serial No. 385,263.

This invention relates to a pamphlet binder and concerns itself primarily with means for confining the wires that hold the pamphlets in the binder.

5 The invention comprises the novel structure and combinations of parts hereinafter described and more particularly pointed out and defined in the appended claims.

In the accompanying drawings which illustrate a preferred embodiment of this invention and in which similar reference numerals refer to similar features in the different views:

10 Figure 1 is a fragmentary interior plan view of a pamphlet binder involving this invention.

Figure 2 is an enlarged sectional view taken upon the line II—II of Figure 1 and looking in the direction of the arrows.

15 Figure 3 is an enlarged fragmentary sectional view taken upon the line III—III of Figure 2.

Figure 4 is a perspective view of one of the wire confining devices.

20 In connection with this invention, there is shown a cover member 1 in which the usual longitudinally extending casing 2 is confined. This casing 2 consists of a pair of bowed plates 2a and 2b which resiliently overlap at their edges as is well known in the art. With reference to Figure 2 it will be noted that the lower bowed plate has its lateral margins directed inwardly as indicated at 3 whereby a groove is formed along the interior surface on each side of the casing.

25 The wire-holding device involving this invention consists of a metal plate 5 of a sufficient breadth and design to fit between the sides of the casing with its edges lodged in the grooves 4 as shown in Figure 2. Upon one end of the plate 5 there extends at right-angles a wire-holding loop 6 which is shown as formed integral with the plate 5. The casing is of course provided with suitable apertures to allow the wire loop 6 to extend therethrough. In the present instance, the binder is shown as equipped with three of these wire-holding devices, it will however be understood that this number may be increased or decreased as desired. It will of

course be understood that pamphlet-holding wires are adapted to be retained under the loops 6 for retaining the pamphlets in the binder.

30 It will be appreciated that on account of the fact that the edges of the plate 5 engage the grooves 4 in the sides of the casing, there is no tendency for the loops to rock or twist and they will at all times be held in a true vertical position. In addition, these wire-holding devices can be more readily manufactured and assembled than other forms of devices.

35 I am aware that many changes may be made and numerous details of construction may be varied through a wide range without departing from the principles of this invention, and I therefore do not purpose limiting the patent granted hereon otherwise than necessitated by the prior art.

40 I claim as my invention:

1. In a pamphlet binder having a casing with opposed grooves, a plurality of plates having their edges positioned in said grooves and each plate having an integral wire loop extending beyond said casing for receiving and holding pamphlet-retaining wires.

45 2. In a pamphlet binder, a bowed plate having opposed grooves adjacent its upper margins, a plate having its opposite edges positioned in said grooves, said plate having a closed loop extending upwardly for the purpose set forth.

50 In testimony whereof I have hereunto subscribed my name at Chicago, Cook County, Illinois.

HENRY R. McCLEARY.
